UNITED STATES PATENT OFFICE.

JOHN W. ENRIGHT, OF NEW ORLEANS, LOUISIANA.

RAIL-JOINT.

1,083,811.

Specification of Letters Patent.

Patented Jan. 6, 1914.

Application filed July 25, 1913. Serial No. 781,159.

To all whom it may concern:

Be it known that I, JOHN W. ENRIGHT, a citizen of the United States, and a resident of New Orleans, in the parish of Orleans and State of Louisiana, have invented a new and Improved Rail-Joint, of which the following is a full, clear, and exact description.

This invention relates to railway construction and has particular reference to novel and improved means for connecting the adjacent ends of the railway rails.

Among the objects accomplished by this invention is the provision of a rail joint which may be rolled and which, when in assembled position, serves to clamp the rails in a peculiar vise-like manner.

The foregoing and other objects of the invention will hereinafter be more fully described and claimed and illustrated in the drawings forming a part of this specification in which like characters of reference indicate corresponding parts in all the views, and in which—

Figure 1 is a transverse section of a railway rail showing in elevation a preferred embodiment of this invention applied thereto; Fig. 2 is a side view of the same; Fig. 3 is a transverse section of a modification of the invention taken on a line corresponding to the line 3—3 of Fig. 2; Fig. 4 is a similar view of a further modification on a line corresponding to the line 4—4 of Fig. 2, it being understood, however, that the actual sections on the lines 3—3 and 4—4 would disclose a form of clamp corresponding to Fig. 1; and Fig. 5 is a detail of the construction of Fig. 1 taken on the line 5—5 of Fig. 2, but indicating a variation in fastening devices.

Having particular reference to Fig. 1, it will be noted that this invention comprises a pair of bars 10 and 11, each adapted to embrace, by wedging action, a side of a rail R, and each including a base plate extending beneath the base flange 12 of the rail. Each bar at its upper edge 13 hugs snugly beneath the head of the rail and at its intermediate portion it constitutes a heel 14 snugly coöperating with the upper surface of said base flange 12. The portion of this bar between its upper edge and its heel is preferably spaced from the web 15 of the rail, as shown in the transverse views. The bar 10 is projected outwardly in a horizontal plane at 16 from the heel 14 and is bent

thence downwardly, merging into a base plate 17 providing a horizontal space 18 opposite the adjacent edge of the base flange of the rail. The other bar 11 is likewise provided with a horizontal outwardly extending member 19 forming a space 20 opposite the edge of the base flange on the other side of the rail. A base plate 21 formed at and integral with the extension of the bar 11 may have connected thereto a neck 22 of such length as to bring the base plate 21 far enough below the base plate 17 to provide a space 23 between said base plates. The space 23 may be maintained between said plates by any suitable positive means such, for instance, as loose washers 24 and lugs 25 formed on either of the base plates and extending into contact with the other.

As shown in Fig. 1, I provide the base plate 21 with an integral lug or rib 25 extending upwardly into engagement with the outer portion of the heel extension 16 of the bar 10. If, desired, however, the washers and lugs may be omitted, allowing the plates 17 and 21 to engage each other, the neck 22 being made short enough for this purpose.

The base plate 21 is preferably extended laterally along both of its edges so as to provide flanges 26 through which any suitable type of fasteners may be driven or passed in order to secure the structure to the cross ties (not shown), these flanges being provided with vertical holes 26' for this purpose. The horizontal extensions 16 and 19 of the bars are provided with rows of vertical holes 27, and the portions of the base plates 17 and 21 are provided with corresponding holes 17' and 21', respectively, in vertical alinement with the holes 27. Through these several sets of aligned vertical holes are passed any suitable form of clamping members, such as bolts 28 or screws 28' for the purpose of drawing those portions of the joint members which have engagement with the rail into close gripping contact therewith. The vertical portions of the bars 10 and 11 are also provided with bolts 29 which extend therethrough and through the web 15 of the rail for the purpose of binding these parts 105 in the positions indicated. It will be observed, therefore, that the fastening devices coöperate with parts of the rail joint which are so spaced as to provide a peculiar vise-like clamping effect by reason of the spaces referred to. It will be noted, also, that this type of rail joint gives the rail a positive

support at three different angles. The space 23, furthermore, provides for a practical cushioning effect for the support of the rail.

That form of the invention shown in Fig. 3 is one in which the bars 10' are substantially alike, each having a base plate 30 extending beneath the base flange 12 of the rail in substantially close contact therewith, the plates 30 of both members being in the same horizontal plane. These members 10' are so shaped and arranged as to provide horizontal spaces 18 substantially similar to the space 18 in Fig. 1, and for similar purposes. Clamping members 28 and 29 are employed in this form of the invention as before described. The rail R in any form of the invention may be provided with fiber or other insulation for use in connection with electrified railroads.

In Fig. 4 I show a pair of joint bars 10' of the same form, but instead of these bars being provided with plate members extending beneath the rail, they are designed to contact with the upper surface of a flat base plate 31 which may substantially correspond in form and extent to the plate 21 described in connection with Fig. 1. In this form of the invention, also, I provide intermediate spaces 18' through which the clamping bolts 28 operate with an effect corresponding to the effect in Figs. 1 and 3.

The modification of Fig. 5 relates to a structure substantially similar to that shown in Figs. 1 and 2, but differs from said construction in the employment of lag screws 28' for securing the structure to the railway ties instead of using the bolts 28 shown in the other figures.

Having thus described my invention, I claim as new and desire to secure by Letters Patent:

1. The combination with a railway rail having a head and a base flange, of a rail joint comprising an angular bar extending along the rail and in contact with said head, said bar having a heel engaging the upper surface of said base flange, said bar having a member extending outwardly from the heel and thence downwardly and inwardly forming a base plate below the lower surface of the rail base flange and providing a space alongside of and in the same plane of the

base flange, said base plate extending beyond the opposite edge of the base flange; a second bar fitted to the opposite side of the rail and having upper edge and heel portions arranged similarly to those of the first bar but being provided with an integral base plate extending below and in spaced relation to the base plate of the first bar, means to maintain said base plates in spaced relation, and clamping means passing through the lateral extensions of the heel portions of the bars and also through both of said base plates serving to bind the heel and plate portions to the rail base by clamping action beyond the lateral edges thereof.

2. The herein described rail joint comprising an angular bar extending along the rail and in contact with the rail head, said bar having a heel embracing the upper surface of the rail base flange, said bar furthermore having an outwardly extending horizontal member and extending thence downwardly and inwardly forming a horizontal base plate fitted snugly against the lower surface of the rail base flange and providing a space alongside of and in the same plane as the base flange, said base plate extending beyond the opposite edge of the base flange; a second bar fitted to the opposite side of the rail and having its upper edge and heel portions of a similar form to those of the first bar but being provided with an integral base plate extending below and in spaced relation to the base plate of the first bar; means cooperating between said base plates serving to maintain such spaced relation; clamping means passing through the horizontal extensions of the heel portions of the bars and also through both of said base plates serving to bind the heel and plate portions to the rail base in a cushion-like resilient manner, and means securing the upper portions of the bars in binding engagement with the upper portions of the rail.

In testimony whereof I have signed my name to this specification in the presence of two subscribing witnesses.

JOHN W. ENRIGHT.
